UNITED STATES PATENT OFFICE

2,063,220

PIPE WRENCH

Vincent Barten, Huntington, Ind.

Application April 28, 1936, Serial No. 76,792

3 Claims. (Cl. 81—106)

This invention relates to pipe wrenches, and it is primarily an object of the invention to provide a wrench of this kind which is of a quick adjusting type.

5 It is also an object of the invention to provide a wrench of this kind comprising an elongated shank carrying a jaw together with a housing movable along said shank and a movable jaw travelling with the housing, said housing and shank having coacting means for adjusting the movable jaw with respect to the jaw of the shank.

10 The invention consists in the details of construction and in the combination and arrangement of the several parts of my improved pipe wrench whereby certain important advantages are attained and the device rendered simpler, less expensive and otherwise more convenient and advantageous for use, as will be hereinafter more fully set forth.

15 The novel features of my invention will hereinafter be definitely claimed.

In order that my invention may be the better understood, I will now proceed to describe the 20 same with reference to the accompanying drawing, wherein:—

Figure 1 is a view in side elevation of a wrench constructed in accordance with an embodiment of my invention;

25 Figure 2 is a view in front elevation of the wrench as illustrated in Figure 1 with lower portions of the housing in section;

Figure 3 is a view similar to Figure 1 with certain of the parts in section;

30 Figure 4 is a detailed sectional view taken substantially on the line 4—4 of Figure 1;

Figure 5 is a detailed sectional view taken substantially on the line 5—5 of Figure 1.

35 As disclosed in the accompanying drawing, my improved wrench comprises an elongated shank 1 having its jaw end portion 2 transversely enlarged for extension beyond a front edge of the shank 1. The jaw end of the shank 1 is disposed on a predetermined angle with respect to the shank 1 and said jaw end is provided therealong with a kerf or recess 3 which snugly receives a flange 4 formed with and depending from the transverse central portion of a jaw plate 5, the outer or working face 6 of which 40 being serrated or otherwise roughened. This jaw plate 5 is held in place by a pin 7 extending through the jaw extremity of the shank 1 and the flange 4. A front edge of the shank 1 at a point immediately adjacent to the enlarged 45 portion 2 and for a desired distance therealong

is provided with the teeth 8 to interlock with the teeth 9 provided along a face of the clutch block 10.

This block 10 is snugly received between the free end portions of the side plates 11 of a substantially U-shaped housing H and this clutch block 10 is held to the side plates 11 by a headed member or bolt 12 around which the clutch block 10 has limited swinging movement. The clutch block 10 in its outer portion has disposed therethrough a pin 14 extending beyond the opposite faces of the block with the extended extremities of the pin being received within the openings 15 in the side plates 11. As is clearly illustrated in Figure 1, each of these openings 15 is of a diameter slightly greater than the diameter of the extremity of the pin 14 within said openings 15. While this pin 14 serves to hold the clutch block 10 in effective working position, yet the block 10 has limited play due 20 to the increased diameter of the opening 15 just referred to.

The back edge face 16 of the shank 1 from the jaw end thereof and for a considerable distance therealong is straight and in contact with this straight rear face 16 is a movable shank section 17. The outer end of the movable shank section 17 is formed with a kerf or pocket 18 in which is received a reduced extension plate 19 carried by a second or outer movable shank section 20. Disposed through the plate 19 and the portion of the shank 17 with which said plate interferes is a headed pin or bolt 21 whereby the shank sections 17 and 20 are pivotally connected one to the other.

35 The adjacent pivoted end portions of the shank sections 17 and 20 are straddled by the housing H and the headed pin or bolt 21 is also disposed through the adjacent portions of the side plates 11 of the housing H.

The outer end portion of the shank section 20 is formed to provide a laterally disposed jaw 22 to overlie the jaw end of the shank 1. This jaw 22 has associated therewith a jaw plate 23 having its outer face 24 serrated or otherwise 40 roughened. This plate 23 carries side marginal flanges 25 which lap the side faces of the jaw 22 so that the plate 23 can be effectively maintained in applied position by the pin 26 disposed through said flanges 25 and jaw 22. The shank 50 sections 17 and 20 are normally maintained in longitudinal alignment by a flat spring 27, one end portion of which bearing against the rear edge face of the shank section 20 and the plate 19 while the opposite end portion of the spring 55

27 is anchored to the rear face of the shank section 17 by the clamping bolt 28 herein disclosed as threading into the shank section 17 with its head 28' having clamping contact with 5 the spring 27.

The head 28' of the bolt 28 has threaded there-through a shank or screw 29. In direct contact with an end of this shank or screw 29 is the tip of a pointed head 30 carried by an end portion 10 of an elongated bolt 31. The upper portion of this bolt 31 is snugly but slidably disposed through the central portion of a pin 32 carried by and intersecting the space between the plates 11 of the housing H and positioned outwardly of 15 the shank sections 17 and 20. Surrounding this bolt 31 and interposed between the head 30 thereof and the pin 32 is a coil spring 34. This spring 34 is of such tension to maintain the point of the head 30 in contact with the shank or screw 20 29 to normally maintain the clutch block 10 in locking engagement with the toothed edge face 8 of the shank 1.

As is clearly illustrated in the accompanying drawing, the housing H is of such formation and 25 dimensions to have movement transversely of the shank 1 and the shank sections 17 and 20 sufficient to disengage the clutch block 10 from the shank 1 upon, of course, the required manipulation of the housing and to facilitate this operation each of the side plates 11 of the housing is 30 provided with the corrugations 35 to prevent slippage of the fingers when adjusting the wrench.

From the foregoing description it is thought 35 to be obvious that a pipe wrench constructed in accordance with my invention is particularly well adapted for use by reason of the convenience and facility with which it may be assembled and operated, and it will also be obvious that my invention 40 is susceptible of some change and modification without departing from the principles and spirit thereof and for this reason I do not wish to be understood as limiting myself to the precise arrangement and formation of the several parts herein shown in carrying out my invention in practice except as hereinafter claimed.

I claim:

1. A wrench comprising an elongated shank having a jaw at one end, an edge of the shank 50 being toothed therealong, the opposite edge face of the shank being straight, a movable shank section having contact with the straight edge face of the shank, an outer movable shank section carrying a jaw for coaction with the jaw at 55 the end of the shank, a housing straddling the shank and the adjacent end portions of the movable shank sections, a pin carried by and disposed through the housing, said pin being also directed through the adjacent end portions of 60 the movable shank sections for pivotally con-

necting said sections one to the other, a flat spring coacting with the adjacent end portions of the shank sections, means for securing an end portion of said spring to one of the sections, and a clutch block carried by the housing and having a toothed face for coaction with the toothed edge face of the shank, said housing having movement transversely of the shank a distance sufficient to disengage the clutch block from the shank. 10

2. A wrench comprising an elongated shank having a jaw at one end, an edge of the shank being toothed therealong, the opposite edge face of the shank being straight, a movable shank section having contact with the straight edge 15 face of the shank, an outer movable shank section carrying a jaw for coaction with the jaw at the end of the shank, a housing straddling the shank and the adjacent end portions of the movable shank sections, a pin carried by and disposed through the housing, said pin being also directed through the adjacent end portions of the movable shank sections for pivotally connecting 20 said sections one to the other, a flat spring coacting with the adjacent end portions of the shank sections, means for securing an end portion of said spring to one of the sections, a clutch block carried by the housing and having a toothed face for coaction with the toothed edge 25 face of the shank, said housing having movement transversely of the shank a distance sufficient to disengage the clutch block from the shank, a pin intersecting the housing outwardly 30 of the movable shank sections, an elongated bolt slidably disposed through said pin, and a spring operatively engaging the pin and the bolt for maintaining the bolt in operative engagement 35 with the first named movable shank section to create a tension to normally maintain the clutch block in locking engagement with the toothed 40 edge face of the shank.

3. A wrench comprising an elongated shank having a jaw at one end, a shank section for movement along the shank, an outer movable shank section carrying a jaw for coaction with 45 the jaw at the end of the shank, a housing straddling the shank and the adjacent end portions of the movable shank sections, a pin carried by the housing and directed through the adjacent end portions of the movable shank sections for pivotally connecting 50 said shank sections one to the other, a clutch block carried by the housing for locking coaction with the shank, said housing having movement transversely of the shank a distance sufficient to disengage the clutch block 55 from the shank, and means coacting with the housing and the first shank section for normally maintaining the clutch block in operative engagement with the shank.

VINCENT BARTON. 60
